UNITED STATES PATENT OFFICE.

JOHN MASON, OF CAPE MAY, NEW JERSEY.

MOORING STATION FOR DIRIGIBLES.

Application filed July 8, 1921. Serial No. 483,140.

To all whom it may concern:

Be it known that I, JOHN MASON, a citizen of the United States, residing in Cape May, in the county of Cape May and State of New Jersey, have invented certain new and useful Improvements in Mooring Stations for Dirigibles, whereof the following is a specification, reference being had to the accompanying drawings.

10 My invention relates to mooring stations for air craft more especially of the type known as dirigibles. Air ships, on account of the enormous size of their gas bags or envelopes, are susceptible to being buffeted by spasmodic wind disturbances, and hence liable to complete destruction if not adequately protected against such contingencies. For this reason, it has in the past been deemed safest to completely house the dirigibles when at rest, and accordingly large hangars were provided for this purpose. Such 15 housings were not only expensive to build but on account of their immobility difficult of access especially in stormy weather and a dirigible could not be berthed without danger of damage or destruction by high winds blowing from adverse directions.

The primary object of my invention is to 20 obviate the objections and difficulties above pointed out and this desideratum I attain by provision of a mooring station which is capable of being aligned with the wind so that landings or launchings may be made under any weather conditions, and which 25 is further capable of completely berthing a dirigible and moreover has facilities for adequately protecting the dirigible against the wind after the latter has been berthed. My invention is susceptible of being embodied 30 in various forms useful both at sea and on land, each of the embodiments having the characteristics above noted, and certain of them the further advantage of being able, under certain conditions, of aligning themselves automatically with the wind.

Other objects and attendant advantages of my invention will become readily apparent from the detailed description which follows.

35 In the drawings, Fig. 1 is a side elevation of one type of mooring station for dirigibles in the form of a mother ship completely equipped for self-propulsion.

Fig. II is a plan view of the structure 40 shown in Fig. I.

Fig. III is a longitudinal sectional view

through the forward end of the ship indicated by the arrows III—III in Fig. II, showing certain important structural details.

Fig. IV is a cross sectional view through the ship viewed in the direction of the arrows IV—IV in Figs. I and II.

Fig. V is a cross section along the line V—V in Figs. I and II.

Fig. VI is a detail view showing a novel form of reinforced, fire proof sheeting which I employ as a lining for a protective wind shield for the dirigible.

Fig. VII is a cross sectional view of the 70 lining.

Fig. VIII is a cross section on an enlarged scale of one of the metallic reinforcing strips incorporated in the lining.

Fig. IX is a diagrammatic view showing, 75 by way of example, one method of interconnecting the lining sheets.

Fig. X is a plan view of a modified form of my invention in the form of a float capable of being towed from place to place.

Fig. XI is a side elevation of the above 80 modification.

Fig. XII is a plan view of still another modified form of my invention adapted for use on land; and

Fig. XIII is a side elevation of the same.

Referring first to the type of my invention illustrated in Figs. I to V inclusive, the mooring station there shown is in the form of a mother ship whose hull 1, it will 90 be noted, is generally of standard design and construction. The bow of the ship is arched by a superstructure 2 whose forward end, tapers toward the stem of the ship as clearly shown in Figs. I, II and III. Said 95 superstructure 2 is built preferably of standard steel shapes and is cross braced after a well known manner as suggested in the illustration so as to be thoroughly rigid against displacement or deformation. The skeleton frame work thus afforded is lined along the interior, as indicated conventionally at 3 in Fig. III, with appropriate fire-proof sheeting and serves as a wind shield for the protection of the forward end or nose 100 of the gas bag or envelope of the dirigible indicated comprehensively by the letter "D". The lining referred to may be of any material suitable for the intended purpose, although I prefer to use sheeting such as illustrated in Figs. VI and VII. In this sheeting, a layer of reinforcing wire mesh 5 is

interposed between layers 6, 7 of the fire proof fabric for example, woven asbestos or the like, a suitable adhesive cement being employed to secure the component layers 5 together. Greater stiffness and rigidity are afforded by incorporation in the wire mesh, both longitudinally and transversely thereof, of metallic strips 8-8 having an arched cross section as clearly shown on an enlarged 10 scale in Fig. VIII. If still greater rigidity should be required, the sheeting may be corrugated or otherwise indented. One convenient way in which sections of the reinforced fabric may be united in the course 15 of being attached to the frame work of the wind shield is suggested diagrammatically in Fig. IX. The joints indicated at 9 are made simply by overlapping and turning over contiguous ends of adjacent sheets. In 20 practice, I prefer to coat the surface of the material which is exposed to the exterior with a suitable paint or sizing so as to render the same impervious to moisture. Any approved means may be employed in securing 25 the lining to the skeleton frame of the wind shield, for this reason, a detailed showing as to the precise manner of attachment has been omitted from the drawings.

Within the wind shield is hung a bumper 30 net 10, preferably of asbestos rope, which is supported by lines or ropes 11-11. By virtue of its characteristic capacity for yielding, said net 10 conforms readily to the shape of the nose of the dirigible "D" and 35 serves to absorb shocks incidental to berthing of the craft thus protecting the same against injury.

Secured at intervals along opposite sides of the ship are posts or poles 12-12 between 40 which are hung rope slings 13-13, the latter being crossed, as best seen in Fig. II, to form 45ointly a cradle for supporting the dirigible. The slings 13 are adjustable as to length (suitable pulleys being used after a manner 50 common to ship rigging) so that they may be drawn or relaxed as found necessary. In order to facilitate landing of the dirigible on the ship, it is desirable that the posts or poles 12 be temporarily moved out of the 55 way. To this end, I have mounted them so that they may be swung to a horizontal position, upon shafts 15 which extend to the exterior of the ship's hull 1 for actuation under suitable operating means, not shown.

After being properly placed upon the supporting sling cradle, the dirigible is 60 securely lashed to both sides of the ship, by a series of guy ropes or cables 16-16. The main deck 17 of the ship, in order to 65 accommodate the cabins and various other appendages of the dirigible, is recessed as clearly shown in Figs. III, IV and V. The interior of the hull is subdivided or partitioned as suggested in several illustrations 70 of the drawings, to afford quarters for crew

storage rooms for equipment and supplies necessary to navigation of air craft, also machine shops wherein repairs may be made as well as space for boilers and engines whereby the ship is propelled. 70

Movements of ships are controlled from a pilot house 20 centrally located directly forward of the wind shields 2 and which is accessible from the main deck by way of ladders 21-21. Gang ways 22-22 lead 75 from the pilot house to opposite sides of the wind shield, and still another gang way 23 leads centrally to the very top of the wind shield to a station of vantage wherefrom the commandant may readily direct 80 various operations incidental to the landing of the dirigible. With a view toward preserving absolute symmetry of design, I make use of two smoke stacks 25-25, one at each side of the wind shield at the bow of the 85 ship, said stacks being flattened as best seen in Fig. I so that the necessary flue area may be obtained within the confines of the restricted available spaces at these regions.

A mooring station in the form of a mother 90 ship such as above set forth having facilities for self-propulsion may, in emergencies, be readily maneuvered to maintain the protective shield 2 in "a head on" position, and the 95 dirigible maintained in alignment with the wind to the exclusion of any possibility of damage or destruction. When at rest, the ship is free to swing about its anchor as a fulcrum in obedience to the influence of the wind so that the alignment of the dirigible 100 with respect to the wind, under this condition becomes absolutely automatic.

For the purpose of preventing side drifting of the ship when at anchor, I have provided at opposite sides of the bow in line 105 with the rear of the wind shield, wings or fins 26-26 which are hinged to the hull and thus capable of being swung back when not in use. They are held extended in the 110 positions shown, by means of braces 27-27, which in practice, may be made either detachable or collapsible so as to permit swinging as aforesaid.

In the modification shown in Figs. X and 115 XI, the mooring station is in the form of a float comprising a main section 30, and a series of auxiliary pontoon or float sections 31-31 which are interchangeable and hence may be increased or decreased in number according to the length of the dirigible 120 which is to be moored. The auxiliary pontoon or float sections 31-31 are coupled rigidly to one another and to the main float section 30 by fastening devices 32-32 of appropriate design which will allow of readily connecting or disconnecting. The main section 30 has, at its bow end, a wind shield 33 which is identical in construction throughout to that represented in Figs. I 125 and II. Although omitted from the draw- 130

ings, in this instance, a rope sling cradle, together with associated appurtenances such as hereinbefore described, is to be used for supporting the dirigible, and guy ropes also for the purpose of lashing the same to the float. The float type of mooring may be readily towed from place to place, and, with the exception of capacity for self-propulsion, has all the advantages hereinbefore attributed to the first embodiment of my invention.

Referring now to the organization designed for land use shown in Figs. XII and XIII, a platform 40 takes the place of the hull and floats of the previous embodiments. Said platform, at its forward end, is considerably enlarged as indicated at 41 so as to be capable of supporting, in addition to the wind shield 42, a number of buildings 43—43, 44—44, which are serviceable as shops and store rooms for supplies and equipment. The platform has facilities for lashing the dirigible after a manner already well understood and is mounted on trucks 45—45 which run on circular tracks 46—46 disposed concentrically about a fixed pivot 47. In practice, the trucks 45—45 may be operated in any convenient manner, preferably electrically, to move the platform about the pivot 47 to align the supported dirigible with the wind for the purpose of safety as already well understood.

Having thus described my invention, I claim:

1. A mooring station for dirigibles, comprising an automatically orientating anchorage, a shield mounted thereon to receive and enclose only the nose of the dirigible, collapsible cradle slings for supporting the dirigible and means for securing the dirigible to the anchorage.

2. A mooring station for dirigibles comprising a support capable of completely berthing a dirigible, said support being sustained with capacity for automatic orientation with the wind to facilitate landing or launching of the dirigible, and provided with a wind shield in the form of a bumper protective shell conformed to receive the nose end only of the dirigible, and a flexible cradle for supporting the dirigible at anchor.

3. A mooring station for dirigibles, comprising a freely movable anchorage, a shield mounted thereon adapted to receive and enclose the nose only of the dirigible, whereby the latter may be guided thereinto without injury, a lining of flexible material within the shield preventing contact between the latter and the dirigible, collapsible cradle slings for supporting the dirigible, and means for securing the dirigible to the anchorage.

4. A mooring station for dirigibles comprising a support capable of completely

berthing a dirigible and provided with a wind shield conformed to adequately receive the end or nose only of a dirigible; a bumper net spanned within the wind shield adapted to absorb shocks incidental to berthing, and a plurality of collapsible crossed slings forming a cradle for supporting the dirigible.

5. A mooring station for dirigibles in the form of an automatically orientating float of adequate length for completely berthing a dirigible having at one extremity an enclosure adapted to receive the fore end or nose only of the dirigible, and a collapsible cradle for supporting the dirigible at an anchor.

6. A mooring station for dirigibles in the form of a float capable of completely berthing a dirigible and having its main deck recessed to accommodate the appendages of the dirigible and provided at its bow with an enclosure of appropriate form for receiving and protecting the forward end or nose only of the dirigible.

7. A mooring station for dirigibles comprising a support capable of completely berthing a dirigible and of automatically aligning to the direction of the wind; a bumper wind shield conformed to adequately receive and enclose the end or nose only of the dirigible; a collapsible cradle of crossed slings having the capacity of adapting itself to the shape of the dirigible to support the remaining portion; and means for holding the dirigible securely to said cradle.

8. A mooring station for dirigibles comprising a support capable of completely berthing a dirigible and of being aligned in the direction of the wind; a wind shield conformed to adequately receive the end or nose of the dirigible; a series of posts disposed at intervals at each side of the support to the rear of the wind shield, said posts being pivoted so that they may be swung out of the way preparatory to landing or launching the dirigible; adjustable rope or cable slings crossed between, and suspended from the tops of said posts forming jointly a supporting cradle for the dirigible; and means for holding the dirigible securely to said cradle.

9. A mooring station for dirigibles comprising a support capable of completely berthing a dirigible and of automatically aligning with the direction of the wind; a bumper wind shield conformed to adequately receive and enclose the end or nose only of the dirigible; a cradle for supporting the dirigible disposed to the rear of the wind shield, said cradle having the capacity for being collapsed preparatory to and for the purpose of facilitating landing or launching of the dirigible, and means for securing the dirigible securely to said cradle.

10. A mooring station for dirigibles in

the form of a float of suitable length for completely berthing a dirigible; a wind shield, at the bow of the float, conformed to adequately receive the forward end or nose of the dirigible; and wings or fins projecting from opposite sides of the float in line with the rear of the wind shield, serviceable in preventing sidewise drifting of the float when at anchor, said wings or fins being hinged so as to be swingable to an inoperative position when the float is in motion. 10

In testimony whereof I have hereunto signed my name at Cape May, New Jersey, this 27th day of June, 1921.

JOHN MASON.
